WIND GUST LOCK FOR AIRCRAFT CONTROL SURFACES

James H. Kinder, 322 8th St., Des Plaines, Ill. 60016;
Kenneth A. Johnson, 155 Big Oaks Road, Cary, Ill.
60013; and Everett A. Johnson, 15 S. Prospect Ave.,
Park Ridge, Ill. 60068

Filed May 6, 1968, Ser. No. 11,802

Term of patent 14 years

Int. Cl. D8—03

U.S. Cl. D8—229

FIG. 1 is a top perspective view of the wind gust lock for aircraft control surfaces embodying our new design;

FIG. 2 is a bottom perspective view thereof;

FIG. 3 is an end view of the gust lock in FIG. 1; and

FIG. 4 is a view of the opposite end.

We claim:

The ornamental design for a wind gust lock for aircraft control surfaces, as shown.
